UNITED STATES PATENT OFFICE.

TIMOTHY C. VAUGHN, OF MORRIS, MINNESOTA, ASSIGNOR TO VAUGHN MANUFACTURING COMPANY, OF MORRIS, MINNESOTA, A CORPORATION OF MINNESOTA.

GRAIN-SEPARATOR.

1,306,870.

Specification of Letters Patent. Patented June 17, 1919.

Application filed August 28, 1916. Serial No. 117,234.

To all whom it may concern:

Be it known that I, TIMOTHY C. VAUGHN, a citizen of the United States, residing at Morris, in the county of Stevens and State 5 of Minnesota, have invented certain new and useful Improvements in Grain-Separators; and I do hereby declare the following to be a full, clear, and exact description of the invention, such as will enable others 10 skilled in the art to which it appertains to make and use the same.

My invention relates to grain separators and is in the nature of an improvement on my prior United States Letters Patent, 15 Number 914,997, issued to me March 9, 1909, and entitled "Grain separator."

To the above end, the invention consists of the novel devices and combinations of devices hereinafter described and defined in 20 the claims.

In the accompanying drawings, which illustrate the invention, like characters indicate like parts throughout the several views.

Referring to the drawings,

25 Figure 1 is a view of the invention in longitudinal central section;

Fig. 2 is a fragmentary plan view of the separating apron and frame therefor removed from the machine; and

30 Fig. 3 is a transverse vertical section taken on the line 3—3 of Fig. 2.

The frame 1 of the machine supports a hopper 2, having in its bottom a feed opening with a feed roller 3 journaled therebelow. A vibratory shoe 4 is suspended by links 5 from the side members of the hopper 2 and, as shown, carries upper and lower sieves 6 and 7, respectively. Materials in the hopper 2 to be separated are evenly distributed by the feed roller 3 over the full width of the screen 6. Suspended from the shoe 4, are two pans 8 and 9. Foul seeds, dirt, etc., screened through the sieves 6 and 7, are caught in the pan 8 and deposited 45 at one side of the machine. Grain, wild oats and other materials carried over the sieves 6 and 7 are caught in the pan 9 and precipitated thereby onto the inclined upwardly moving surface of a separating apron 10.

50 The separating apron 10 runs over upper and lower rollers 11 and 12, respectively. The shaft 13 of the upper roller 11 is journaled in bearings 14 secured to the rear leg of the frame 1. A pair of side boards 55 15 is located at the ends of the rollers 11

and 12, above the shafts thereof. The shaft 16 for the roller 12 is journaled in adjustable bearings 17 secured to the lower edges of the side boards 15 and at the lower ends thereof. Bearing lugs 18 pivotally connect 60 the side boards 15 to the shaft 13 for vertical swinging movement.

The inclined upwardly moving surface of the separating apron 10 is directly supported on a deck 19 carried by the side boards 15. 65 It is important to note that the upper surfaces of the rollers 11 and 12 are tangential with the upper surface of the deck 19 and that said deck extends substantially the entire distance between the said rollers. By 70 thus locating the deck 19, the separating apron 10 in passing thereover is supported without sag, wrinkles, creases or pockets, which is highly desirable in the separation of grain. By adjusting the bearings 17, 75 the desired tension may be placed on the separating apron 10. It may be here stated that by supporting the separating surface of the apron 10 on the deck 19, said apron can be much looser on the rollers than the apron 80 in my prior patent above identified, thereby making the machine run much easier. In said prior patent, it was necessary to keep the separating apron very tight to take out the sag, wrinkles and creases therein. 85

The separating apron 10 is preferably made from canvas or other fabric, having a relatively hard smooth surface. The separating surface of the apron 10 is held at the desired inclination by a pair of cables 20 attached to the side boards 15 and arranged to be wound upon a crank-equipped windlass shaft 21 journaled in bearings 22 on the frame 1. A ratchet device or other suitable means, not shown, may be provided for holding the windlass shaft 21 in different adjustments. The separating apron 10 extends the full distance between the side boards 15 and notches or apertures 23 are formed obliquely in the longitudinal edges of the deck 19 to 100 permit the escape of grain, in case any thereof should work between the apron and deck.

Secured to the frame 1, is a fan casing 24 in which is mounted a fan 25. The fan casing 24 is provided with a horizontally disposed discharge spout 26, which extends between the side boards 15 and directs the blast of air from the fan 25 onto the separating apron 10, while passing over the deck 19. It will be noted that the blast of air is 110

directed over substantially the full area of the deck 19 and a portion thereof is directed between the pan 9 and roller 11 to remove from the precipitated grain dust and other light materials, not removed by the screens 6 and 7.

For the purpose of this case, it is not thought necessary to illustrate the driving connections for the feed roller 3, roller 11 and fan 25 and the connection for vibrating the shoe 4.

The materials precipitated onto the separating apron 10 are caught by the oblique blast of the air from the fan 25 and all wild oats, shrunken kernels of grain, sticks, straws, etc., are held on said apron by the blast of air and carried upward over the roller 11 and deposited at the rear of the machine. As the surface of the apron 10 is relatively hard, the wild oats will not stick thereto. The clean healthy kernels of grain, having the specific weight, roll down on the apron 10 and are deposited onto the floor under the machine or into a receptacle placed to receive the same. By changing the inclination of the separating surface of the apron 10, the operator can grade the grain as heavy or as light as he pleases.

As the separating surface of the apron 10 is held perfectly smooth on the deck 19 by the blast of air from the fan 25, there is no danger of the good grain being caught in creases or pockets in the apron and carried upward and over the roller 11 with the material separated from the grain.

Copies of this patent may be obtained for five cents each, by addressing the "Commissioner of Patents, Washington, D. C."

What I claim is:—

1. In a grain separator, the combination with a frame having an upwardly inclined deck with apertures in its longitudinal edges, of a traveling endless separating 40 apron arranged to move upwardly over the deck, and a fan arranged to deliver a blast of air onto the separating apron while said apron is passing over the deck.

2. In a grain separator, the combination with a frame having an upwardly inclined deck and side boards extending upwardly therefrom, of an apron passing over said deck, and a fan having a discharge spout extending between the side boards of the 50 deck, said spout having an opening extending substantially from end to end of the deck, whereby the blast of air from the fan will maintain the apron in contact with the deck.

3. In a grain separator, the combination with a frame having an upwardly inclined deck, of an apron passing over said deck and a fan having a discharge spout, said spout having an open end, inclined to correspond 60 with the degree of inclination of the apron and deck, disposed closely adjacent thereto and extending substantially the length of the deck.

In testimony whereof I affix my signature 65 in presence of two witnesses.

TIMOTHY C. VAUGHN.
